DEFLECTION OF ELECTRON BEAMS

Albert W. Friend, Lawrenceville, N. J., assignor
to Radio Corporation of America, a corporation
of Delaware

Application April 30, 1948, Serial No. 24,145

16 Claims. (Cl. 315—27)

1

This invention relates to deflection of electron beams, and more particularly to an improved deflection method and system which is simple and economical of apparatus and in operation. Provision is also made for rectification to supply either positive or negative high voltage.

Many known combinations of deflection and high-voltage supply systems employ as many as four, five, or more electron tubes, at least two of which must be power tubes, and one of the latter usually is a high-impedance pentode, or beam tetrode. The other power tube usually is a damper, which may also act as a voltage-booster tube. In such systems the power is applied at an intermediate point in the deflection cycle, then at the end of a trace the power is cut off for retrace and stored energy is used for the next trace up to near said intermediate point. This results in a "cross-over" point where the stored energy ceases and power is re-applied, usually to the left of center of the trace path. Inasmuch as the trace should be linear with respect to time, the discontinuity at the "cross-over" point presents difficulties.

The present invention avoids such difficulties by applying the power during retrace and using stored energy for the entire trace, which therefore is continuous and has no "cross-over" point. The invention includes a circuit for accomplishing such result which requires only two tubes, preferably high-current low-impedance power triodes, and they may be alike. Both triodes may, however, be mounted in one envelope.

Hence, the main object of the present invention is to provide a simpler and more economical deflection system.

Another object is to make the trace continuous and linear with respect to time.

A related object is to obtain a high-voltage, low-current supply from the deflection apparatus.

Other objects and advantages of the invention will become apparent from the following description in connection with the accompanying drawing in which:

Figure 1 is a circuit diagram illustrating one embodiment of the invention by way of example; and,

Figure 2 illustrates another embodiment thereof.

In both figures like reference characters indicate similar parts.

Referring to Figure 1, S represents a source of positive synchronizing (sync) pulses which are impressed upon the grid of a power tube 10 through a coupling condenser 11 and secondary winding 12 of a transformer indicated generally

by reference character 15. The source S is terminated by a resistance 16 and connected to one side of condenser 11 and to the cathode of tube 10. The other side of condenser 11 is connected through a resistance 17 to said cathode, which is grounded. The anode of tube 10 is connected to primary winding 18 as its load. The arrangement thus far described may be the usual blocking oscillator circuit for generating a wave (e-1) with sharp negative pulses in the output circuit of tube 10, as indicated on Figure 1.

Transformer 15 has a secondary winding 20 across which is connected, in parallel, a winding 21 of an electromagnetic yoke 22 suitable for deflecting electron beams. This part of the circuit also includes a by-pass condenser 23 for periodic current and a balancing condenser 24 which latter may be connected to the mid-point of winding 21 to balance the distributed capacity of yoke 22 relative to ground.

Across the secondary 20 and winding 21 there are connected, in series, a second power tube 25 and a storage condenser 26. The anode of tube 25 is connected to that end of secondary 20 which is made negative by negative pulses in primary 18. The cathode of said tube is connected to one side of condenser 26, the other side of which is connected to winding 21 and (for periodic current) through condenser 23 to the positive end of secondary 20. The grid circuit of tube 25 may be a known form of linearity network comprising a condenser 28 connected between the anode and grid of said tube, a fixed resistance 29, and two variable resistances 30 and 31 connected in series from grid to cathode of tube 25, and a condenser 32 shunting the resistance 31.

The direct-current anode circuits for tubes 10 and 25 are connected in series as follows. From the positive terminal B+ of a source of anode voltage, the anode current passes through a centering device 35 having two variable taps 36 and 37 connected respectively to the ends of secondary 20 and yoke winding 21, forming two parallel paths for the anode current which are joined together at the other ends of said windings and connected to the anode of tube 25. The cathode of said tube is connected by leads 38 and 39 to one end of the transformer primary 18, the other end of which is connected to the anode of tube 10 as previously mentioned. The circuit is completed by the connection from the cathode of tube 10 to ground which is also connected to the negative terminal B- of the voltage source. This voltage source and the centering device 35 are bypassed by a condenser 41.

It may be desirable to connect a variable balancing resistance 42 between the cathode lead 38 and the tap 37 in order to bleed-off any excess of average anode current in tube 25 over that in tube 10. Other B+ loads can be taken from the point 43 of centering device 35 if desired.

In order to supply a high negative voltage from the deflection system thus far described, a high-voltage secondary winding 45 is provided on transformer 15. Such winding may be a continuation of secondary winding 20 as indicated. A part (usually two or a few turns of heavier wire) of the high-voltage end of winding 45 is connected across a cathode filament or heater 46 of a rectifier tube 47, the anode 48 of which is connected to a filter condenser 50. The other side of condenser 50 may be connected to the grid end of winding 12, as shown, or in some cases to B+ or to ground. The rectified high voltage may be supplied through a lead 51 and high resistance 52 to the cathode 53 of an image tube 55, such as a kinescope. The second anode 56 thereof may be connected to a suitable point of relatively positive potential such as B+ or ground.

The circuit of Figure 2 is the same as Figure 1 as far as the deflecting system is concerned, but the transformer 15 and rectifier tube 47 are arranged to provide a positive high voltage for the tube 55. This arrangement requires a separate winding 57 for heating the cathode 46 of the rectifier. Said cathode is connected to the positive side of condenser 50, the negative side of which is connected to that end of transformer winding 20 which is negative when the primary pulses are negative. The positive end of winding 20 is connected to the negative end of high-voltage winding 45, the positive end of which is connected to the anode 48 of the rectifier. The positive high voltage is taken from the cathode 46 through lead 51 and high resistance 52 to supply the second anode 56. In this case the cathode 53 may be grounded.

It is understood that yoke 22 and winding 21 are assembled with image tube 55 so as to deflect the electron beam from cathode 53 in known manner.

The deflection system shown in Figures 1 and 2 operates as follows. Starting of the anode current drives the grid of tube 10 positive causing grid current to flow. During the time grid current is flowing a negative voltage is built up across resistor 17 and this charges condenser 11. When the anode current ceases increasing and begins to decrease, the transformer windings 18 and 12 drive the grid very negative. The negative charge on the grid and condenser 11 leaks off through resistors 17 and 16, and no action takes place until the grid reaches a potential where anode current can again flow. Then the cycle of events is repeated. The time constant of condenser 11 and resistor 17 is selected to give a frequency slightly lower than the sync frequency. Now if a positive voltage pulse from source S raises the grid voltage to a point where the anode current flows slightly earlier than if such pulse were not applied, the pulse will trigger tube 10 and thereafter the negative pulses (e-1) in its output circuit will be kept synchronous with the source S. The resistance 17 may be made variable, if desired, to permit adjustment of the free oscillating period of tube 10; in which event the resistance is called a "hold control." The output of tube 10 is transformed by windings 18 and 20 and impressed across the yoke winding 21, the polarities of the windings

being such that the pulses make the upper end of winding 20 negative and start the retrace portion of the deflection cycle. The anode of tube 25 is abruptly made negative at this time, thereby making the tube non-conductive. By way of example, the negative pulses (e-2) may be about 1,000 to 4,000 volts. Each pulse stores energy in the yoke 22 as magnetic flux and starts an oscillation the frequency of which is determined by the inductance and distributed capacity of yoke 22 and transformer 15. The oscillating current thus started lags the voltage by almost 90° and provides the current change for retrace of the electron beam in kinescope 55. The other half of the first cycle of voltage oscillation makes the anode of tube 25 positive and therefore conductive, which prevents the voltage from rising very high in a positive direction. Instead, the current through tube 25 charges the storage condenser 26 so that the side of the condenser connected to the tube cathode is positive and the side of the condenser connected to B+ is negative. Thus tube 25 with condenser 26 acts as a damper for the oscillation in the yoke after the first half-cycle of voltage therein. The current in the yoke winding reaches a maximum when the voltage becomes approximately zero and then, instead of decreasing rapidly as in free oscillation, it decreases substantially linearly due to charging condenser 26 at an almost constant potential. Any departure from linearity is corrected by adjusting the linearity control in the grid circuit of tube 25. This controlled flow of current (i) provides the entire trace portion of the deflection cycle for kinescope 55 by means of its yoke 22.

After several cycles of operation the condenser 26 assumes an electrostatic charge which is replenished during each conductive period of tube 25. Another important function of condenser 26 is to supply anode current to tube 10 during the portion of the deflection cycle that the anode of tube 25 is negative and therefore non-conductive. Inasmuch as the D. C. anode circuits of tubes 10 and 25 are connected in series (as previously mentioned) tube 10 would be unable to draw its desired maximum current from the B supply if condenser 26 were not present. A further function of condenser 26 and tube 25 is to boost the anode voltage applied to tube 10, for it will be noted that the B supply and charged condenser 26 are effectively in series in the anode current circuit of said tube. Thus the generation of each current pulse in primary 18 is assisted, and its wave front steepened, by the electrostatic charge stored in condenser 26 from a prior pulse.

During the portions of the deflection cycle that tube 25 is conductive, the anode current from the B+ terminal flows first through the centering device 35, then through windings 20 and 21 to tube 25, from the cathode thereof through leads 38 and 39 to primary winding 18, thence to the anode of tube 10, and returns from the cathode of said tube to the B- terminal. If an excess of average anode current in tube 25 is required it can be supplied by adjustment of the resistance 42 connected as shown. However, by using like tubes which preferably are high-current low-impedance power triodes and proper circuit design, the average anode-currents will be substantially equal and therefore resistance 42 may be very high or eliminated. Also a twin power triode such as the 6AS7-G may be used.

The centering device 35 (by means of its taps 36 and 37) provides the usual control for centering the image in kinescope 55 in known man-

ner. A width control for said tube may be provided by a variable inductance 58 shunted across a portion of primary winding 18.

Referring specifically to Figure 1 it will be noted that the rectifier tube 47 has impressed upon it and condenser 50 the combined voltage of transformer windings 12, 20, and 45, said windings being connected in series relative to the rectified current. This current passes through resistance 17 and the B supply as a connection from winding 12 to winding 20. If it is desired to omit the potential of winding 12, the positive side of condenser 50 may be connected directly to ground or tap 36 or B+. The polarities of the connections just described are such that a high negative potential is developed in the lead 51 relative to the remainder of the system. This potential is applied to the kinescope cathode 53. The second anode 56 is connected to a relatively positive point in the system, such as B+ or ground, thereby providing the high D. C. potential required for operation of the kinescope. It is understood, of course, that the current required for such purpose is very small.

Referring now to Figure 2, the high voltage for kinescope 55 is provided in a similar manner but it has a positive potential relative to the remainder of the system. In the Figure 2 arrangement the cathode 46 of the rectifier 47 is heated by separate filament winding 57. The connections of transformer windings 20 and 45 are reversed, that is, their outer ends are connected together instead of their adjacent ends as in Figure 1. Thus the negative pulses in primary 18 produce positive pulses at the end of winding 45 which is connected to anode 48 of the rectifier. The filter condenser 50 is then charged by the rectified voltage so that the side connected to cathode 46 is positive and the side connected to the upper end of winding 20 is negative. The high positive D. C. potential thus obtained is applied through resistance 52 to second anode 56 of kinescope 55, the cathode 53 of which may be grounded. Such connection adds the B+ voltage to the rectified voltage.

While only two embodiments of the invention have been described and illustrated, it is obvious that many changes and substitutions can be made within the purview of the invention and to meet particular requirements.

What is claimed is:

1. The method for electromagnetically deflecting an electron beam which comprises, generating current pulses of short duration relative to a deflection cycle, storing energy from such a pulse as magnetic flux, and converting said flux into electromagnetic deflection current at a controlled rate continuously throughout the entire trace portion of said cycle.

2. The method according to claim 1 including the steps of storing part of the energy of said deflection current as an electrostatic charge, and using said charge in the generation of a succeeding current pulse.

3. The method for deflecting an electron beam which comprises, generating a current pulse and storing energy therefrom as magnetic flux only during the retrace portion of a deflection cycle, converting said flux into deflection current at a controlled rate continuously throughout the entire trace portion of said cycle, converting a portion of said deflection current into an electrostatic charge, and using said charge at the start of the next retrace to assist in the generation of the next current pulse.

4. The method according to claim 3 wherein the current pulses are generated under direct control of positive sync pulses, and the leading edges of said current pulses are steepened by said electrostatic charge.

5. A deflection system comprising electromagnetic means for deflecting an electron beam, means for generating a current pulse and energizing said electromagnetic means therewith during retrace of said beam, means for discharging the energy in said electromagnetic means, and means for controlling the rate of said discharge continuously during the entire trace of said beam.

6. A deflection system according to claim 5 comprising in addition, a condenser connected to said discharging means, and means for partially discharging said condenser through said generating means to assist in the generation of succeeding pulses.

7. In a deflection system the combination of a first high-current low-impedance power tube having an anode and a cathode, a second high-current low-impedance power tube having an anode and a cathode, an anode-cathode circuit for each tube, a transformer coupling said circuits for periodic current, a source of anode voltage, said circuits being connected in series across said source for direct current, and a condenser shunting the anode-cathode circuit of said second tube whereby said first tube is supplied with anode current when said second tube is non-conductive.

8. The combination defined by claim 7 wherein each tube has a grid, and including a source of positive sync pulses connected to the grid and cathode of said first tube, and a linearity network connected to the grid, anode, and cathode of said second tube.

9. In a deflection system including an electromagnetic deflection yoke the combination of a pair of high-current low-impedance power tubes, each having anode, cathode and grid electrodes, circuits for said electrodes, a source of anode voltage, one of said circuits being a series circuit comprising three serially connected parts, said first part being the connection of said deflection yoke, from the positive side of said source to the anode of one tube, said second part being, from the cathode of said one tube to the anode of the other tube, and said third part being, from the cathode of said other tube to the negative side of said source; and a storage condenser connected between the first and second parts of said series circuit such to embrace the series connection of said deflection yoke and said one tube.

10. In a deflection system including an electromagnetic deflection yoke, the combination of, a first and second high current low impedance power tubes, said first tube having at least an anode, cathode, and control electrode, said second tube having at least an anode and a cathode, a blocking oscillator pulse generating circuit including said first power tube, a damper circuit including said second power tube, connections placing the anode-cathode circuits of said power tubes in series with one another through said deflection yoke, and a storage capacitor connected substantially in shunt with the series combination of said deflection yoke and said second discharge tube.

11. The combination defined by claim 10 including a transformer having primary and secondary windings, said primary being connected in the anode circuit of said first power tube, and

a magnetic deflection yoke having a winding connected across said secondary winding; said second power tube triode and said condenser being connected in series across said yoke winding.

12. The combination defined by claim 11 including a high-voltage secondary winding on said transformer connected in series with the first mentioned secondary winding, and a series-connected rectifier and filter condenser connected across said secondary windings whereby their combined voltage is rectified. 10

13. The combination defined by claim 12 including a third secondary winding on said transformer connected in the control circuit of said first power tube and in series with said first and high-voltage secondary windings to add its voltage to the rectified voltage. 15

14. In a deflection system the combination of a first high-current low-impedance power tube having an anode and a cathode, a second high-current low-impedance power tube having an anode and a cathode, an anode-cathode circuit for each tube, a transformer having a primary winding in the anode circuit of one said tube and a secondary winding in the anode circuit of the other tube, a source of anode voltage, said anode circuits being connected in series across said source, a condenser shunting the anode-cathode circuit of said second tube, a high-voltage secondary winding on said transformer connected in series with the first mentioned secondary winding, and a series-connected recti- 20

25 fier and filter condenser connected across said secondary windings whereby their combined voltage is rectified.

15. The combination defined by claim 14 where- 5 in said rectifier has a cathode connected across a part of said high-voltage secondary winding at the high-voltage end thereof, whereby the rectified voltage has a high negative potential relative to the remainder of the system.

16. The combination defined by claim 14 in- 10 cluding a separate winding on said transformer, said rectifier having a cathode connected across said separate winding and having an anode connected to the high-voltage end of said high-voltage secondary winding, whereby the rectified voltage has a high positive potential relative to the remainder of the system.
